CONTROL APPARATUS FOR VALVES

Lester L. Collins, Franklin, Pa., assignor to Chicago Pneumatic Tool Company, New York, N. Y., a corporation of New Jersey

Application February 25, 1931 Serial No. 518,107

1 Claim. (Cl. 137—153)

This invention relates to mechanism for pumping and compressing gaseous fluids. More particularly it concerns control apparatus for the valves of such mechanism whereby partial or 5 total unloading of the same may be conveniently effected.

One object of the invention is to assemble the control apparatus with the valve cover for application and removal as a unit with the latter.

10 Another object is to reduce the head room for the necessary springs and to dispose the unloading apparatus within the pump or compressor cylinder. Another object is to provide a structural arrangement which will permit the use of 15 various agencies for actuating the valve lifter. Still other objects will be apparent from the detailed description which follows.

The invention involves the mounting of all 20 control mechanism for the valve directly upon the cover which seals the opening through which the valve assembly is inserted into or removed 25 from its recess in the pump or compressor cylinder. The mounting arrangement is such that various devices may be used to actuate the valve lifter, as for example diaphragm, bellows, or piston.

In order to illustrate the invention one concrete embodiment thereof is shown in the accompanying drawing, in which the single view 30 discloses the control apparatus in vertical section and indicates in broken outline the manner in which the apparatus is mounted in a compressor cylinder and its relation to a valve assembly.

35 In the embodiment of the invention chosen for the purpose of illustration, the inner and outer walls *a*, *b* of a compressor cylinder *A* are indicated, the inner wall having a stepped opening *c* therethrough in which an inlet valve assembly 40 *B* of conventional plate type is mounted and retained in place by the usual holding members *d*. To give access to valve chamber *e* for the insertion and removal of valve assembly *B*, the opening *f* is provided in outer cylinder wall *a*. Since 45 the elements heretofore mentioned are wholly conventional, they are indicated in the drawing in broken outline merely for the purpose of showing the general combination and arrangement, and further description thereof is accordingly 50 omitted.

The control apparatus by which the plate valves of valve assembly *B* are held open, as when the compressor cylinder is partially or entirely unloaded, is mounted entirely upon the cover plate 55 *g* which seals opening *f* in the outer wall of com-

pressor cylinder *A*. Plate *g* may be secured to the cylinder in any suitable manner as by conventional stud bolts *2* and has secured to its under side by stud bolts *3* so as to be supported within valve chamber *e* a cylindrical member or housing 60 *4*. Over the lower open end of cylinder *4* is secured as by stud bolts *5* a perforated closure *6*. A valve lifter *7*, provided with fingers *7a* for engaging the valves of valve assembly *B*, is movably mounted on closure *6*, the lifter having an extension or boss *7b* projecting through the perforation or bore *6a* in the closure. A rod *8* secured in bore *7c* in lifter extension *7b* by a pin *9* telescopically receives at its upper end a cap member *10*. Lifter *7* is held in its retracted position by a coil 65 spring *11* which encircles extension *7b* and rod *8* and engages with its lower end closure *6* and with its upper end an abutment washer *12* which is maintained in spaced relation to cap *10* by stop pin *13* extending through a transverse bore in 70 rod *8*.

In order to move valve lifter *7* outwardly to operative position, suitable means are provided within cylinder member *4* to be actuated by fluid pressure admitted through bore *1a* in cover *1*. While 75 a diaphragm may be clamped between cylinder *4* and cover *1* to engage cap *10* for this purpose or a piston head substituted for cap *10* and slidably engaging the inner walls of cylinder *4*, the preferred apparatus comprises an annular bellows *14* which encircles the extended portion of the lifter *7* and the resilient means for retracting the same. By preference the upper end of bellows member *14* is welded, brazed, or otherwise secured in a fluid tight manner as at *14a* to cap 80 *10* and its lower end extends radially to form an annular flange *14b* which is clamped in a fluid tight manner between closure *6* and cylindrical member *4*. Thus the pressure fluid admitted through port *1a* in cover *1* is confined in the space 85 provided between bellows *14* and cap *10* on the one hand and the inner walls of cylindrical member *4* and cover *1* on the other so that it is effective upon cap *10* to overcome the resistance of spring *11* and to force lifter *7* downwardly to operative 90 position. The admission of motive fluid to port *1a* and the venting of the same therefrom may be controlled manually or by an automatically actuated regulator (not shown).

From the above it will be apparent that the present invention provides a convenient disposition of fluid pressure actuated control apparatus for an inlet valve, that the operative parts thereof are adequately protected by being housed within the valve chamber of the cylinder, that 100 105 110

the apparatus is conveniently and easily inserted and removed by simply putting on or removing the cover to the valve chamber, that no parts of the control apparatus extend beyond or form projections above the compressor cylinder, and that the cylindrical member 4 which is secured to the end face of the cover permits the choice of agencies to be subjected to the pressure fluid for controlling the valve, such as a piston or diaphragm, in 10 place of a bellows construction illustrated herein.

While the invention has been herein disclosed in what is now considered to be a preferred form, it is to be understood that the invention is not limited to the specific details thereof but covers 15 all changes, modifications, and adaptations within the scope of the appended claim.

I claim as my invention:

A combined closure and control unit comprising 20 a cover plate for a valve chamber, a cylindri-

cal member secured to one face of said plate, a perforated closure for the open end of said member, a valve lifter having a portion extending through the perforation in said closure, a cap member engaging the end of said portion within said cylindrical member, stop means on said portion adjacent said cap member, a coil spring encircling said portion and interposed between said stop means and said closure yieldingly to maintain said lifter in retracted position, and fluid pressure means including a bellows encircling said spring and secured to said cap member on the one hand and under said closure on the other for acting upon said cap member to force said lifter to extended position against the resistance of said spring, said lifter portion extending loosely through said perforation in said closure to permit tilting of said lifter.
